Primary Examiner — Michael A Pratt(74) *Attorney, Agent, or Firm* — Schwabe Williamson & Wyatt(57) **CLAIM**

The ornamental design for a magazine release lever, as shown and described.

DESCRIPTION

FIG. 1 is a side view of a firearm receiver with a magazine release lever.

FIG. 2 is an enlarged view of the magazine release lever of FIG. 1 shown in isolation from the firearm receiver; and, FIG. 3 is a perspective view of the magazine release lever shown in FIG. 2.

The broken lines showing a lower receiver in FIG. 1 illustrate environment which forms no part of the claimed design. Additional broken lines shown in FIGS. 1, 2, and 3 illustrate portions of the magazine release lever that form no part of the claimed design.
